CLAIM

The ornamental design for a display with a stand as shown and described.

DESCRIPTION

FIG. 1 is a perspective view of a display with stand showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear side perspective view thereof, shown with the stand opened; and,

FIG. 9 is an enlarged detail view of area 9 shown in FIG. 1. The bold even-dash broken lines, showing detail circles and lead lines in FIGS. 1 and 9, represent the extents of the detail views and form no part of the claimed design. The light-weight even-dash broken lines illustrate portions of the display with stand that form no part of the claimed design.
